UNITED STATES PATENT OFFICE.

JAMES M. GAAR, OF NEW YORK, N. Y.

DESIGN FOR A RADIO LOOP.

Application filed August 19, 1924. Serial No. 10,491. Term of patent 3½ years.

To all whom it may concern:

Be it known that I, JAMES M. GAAR, a citizen of the United States, residing at New York, borough of Manhattan, in the county and State of New York, have invented a new, original, and ornamental Design for Radio Loop, of which the following is a specification, reference being had to the accompanying drawings, forming part thereof.

The figure shows a perspective view of the

loop.

I claim:—

The ornamental design for a radio loop, as shown.

JAMES M. GAAR.
